WILLIAM L. OSBORNE, OF LOS ANGELES, CALIFORNIA, ASSIGNOR TO OSBORNE PROCESS, INC., OF LOS ANGELES, CALIFORNIA, A CORPORATION OF CALIFORNIA

METHOD OF CLEANING LUBRICANT CONTAINERS

Application filed August 21, 1929. Serial No. 387,293.

The present invention relates more particularly to a novel method of cleaning lubricant cases of engines, particularly crank cases, transmission and differential cases of motor vehicles, such as automobiles, trucks and the like.

The objects and advantages of the invention will hereinafter more fully appear from the following description, but broadly speaking the purpose is to provide a method of effectively and quickly cleaning the case containing the lubricant together with the mechanism enclosed in such case. To this end the invention is carried out, first, by preferably draining off the dirty oil or used lubricant and then forcibly circulating a cleaning oil through the case and around the mechanism contained therein.

I have found that in cleaning a crank case of an automobile, for instance, it is highly desirable that the flow of cleaning oil be controlled at the point of introduction of the cleaning oil to the lubricant container rather than at the point of pumpage, as has heretofore been the case. The reasons for this are obvious when the conditions of cleaning a lubricant container are taken into consideration. The crank case is first drained of its used oil which may be caught in a suitable receptacle and pumped to storage or disposed of in any suitable manner. Cleaning oil may then be introduced into the crank case with the engine running at a moderate speed. Considerable windage is set up within the crank case by the motion of the connecting rods and crank shaft, which opposes the entrance of the cleaning oil. Assume, for the sake of illustration, that the flow of cleaning oil is controlled at the point of pumpage, which, under the usual conditions would be relatively remote from the crank case. This aforementioned opposition to the initial introduction of the cleaning oil would tend to cause a backup of the oil in the crank case oil filler opening, which the operator, if at the point of pumpage, sometimes does not observe until the oil overflows, drenching the outside of the crank case and wasting oil. Obviously, if the operator was at the point of introduction of the cleaning oil into the

crank case this fact would be immediately noticeable, and if a ready means of control was available to the operator at this point, the flow could be positively and accurately controlled.

Accordingly, one of the important features of the present invention resides in passing cleaning oil through a lubricant container, removing the sediment and foreign matter therein, passing the cleaning oil from the lubricant container through a pump and a filter, thence back to the lubricant container, and controlling the flow of cleaning oil at a point remote from the pump without stopping the pump.

Another important feature of my invention comprises substantially filling a lubricant container with cleaning oil, interrupting the introduction of the cleaning oil and permitting the cleaning oil to substantially entirely drain from the lubricant container and, just at the time when the final quantity of cleaning oil is passing from the lubricant container, suddenly introducing a fresh charge of cleaning oil to the lubricant container and thereby effectively preventing the deposition of sediment upon the interior surface of the lubricant container by washing the suspended particles of foreign matter from the lubricant container while they are still in suspended condition.

Other and further important objects of the invention will be apparent from the accompanying drawings and following description.

In the drawings, Fig. 1 is a diagrammatic side elevational view, illustrating apparatus for carrying out the method of the present invention.

Fig. 2 is an enlarged fragmentary vertical section of the pump and driving motor.

Fig. 3 is a cross sectional view taken on line 3—3 of Fig. 2 looking in the direction of the arrows with the valve housing removed.

Fig. 4 is a fragmentary sectional view of the intake conduit.

Referring more in detail to the drawings, 1 designates as a whole an enlarged drum storage tank which may be provided with base 100.

wheels 2 where the device is portable and a support 3. The drum 1 may be provided with a false bottom 4 which divides the drum longitudinally into two compartments, an upper storage compartment for used lubricant and used cleaning oil, and a lower compartment for the motor.

Disposed within the lower compartment is a platform 5, removably supported at one end upon the axle 6 of the wheels 2, by means of an angle-iron 7 retained in position by a bolt 8, and at the other end by the support 3. Mounted upon the platform 5 is a motor 9 having an external electric connection 10, controlled by switch 11. A duplex lead 12 is connected at one end to a source of electric current (not shown), whereas the other end connects with the switch 11 by means of a usual two-prong removable plug 13.

The shaft 14 of motor 9 may be connected mechanically to an abutting shaft 15 of a gear pump 16, the connection comprising a flexible coupling 17. The pump 16 is provided with an inlet 18 and an outlet 19. A gear 20 may be mounted upon one end of the shaft 15 and may mesh with a cooperating gear 21. Both gears may preferably be of the spiral type. The inlet 18 may communicate with a duct 22 provided in the housing of the pump 16, said duct terminating in a port 23, which communicates with the teeth of both gears 20 and 21 immediately below the point where the same mesh. The outlet 19 communicates with a duct 24 terminating in port 25, which in turn communicates with the teeth of both of said gears, immediately above the point where the same mesh. The housing of the pump is recessed at 26 and 27 wherein the gears 20 and 21 respectively rotate. Oil entering at 18 flows through the duct 22 and port 23 and is carried by the gears, rotating in the direction indicated by the arrows in Fig. 3, to the outlet port 25, thence through duct 24 and outlet 19.

The pump inlet 18 may be arranged to have detachable engagement with a flexible conduit 28, shown best in Fig. 1, the latter being connected to a suitable drip pan 29 in the manner shown or, if found desirable, the conduit 28 may be directly connected to lubricant container to be cleaned. The inlet of conduit 28 within the drip-pan may be provided with an elbow 28' having a screen 29' over its mouth to prevent solid material, such as cotter pins, bolts, metal shavings, or the like, from being drawn through the conduit to the pump and eliminating the possibility of injury to the gears thereof. The pump outlet may be suitably connected to a four-way distributing valve 30, the latter communicating, respectively, with branch pipes 31, 32, 33 and 34 whereby, upon selective manipulation of the valve 30, any of the branches 32, 33 or 34 may be connected to the pipe 31, or in other words, to the discharge of the pump 16.

The branch 32 may communicate with a filter 35 which is especially adapted to filter from the cleaning oil passing therethrough the heavy tar-like substances removed from transmission and differential housings and the like. The pipe 33 may communicate with the drum 1 whereby liquids such as used lubricants or used cleaning oil pumped by the pump 16 may be directed to the storage drum 1. The pipe 34 may communicate with a filter 36 which may be especially adapted to filter from the cleaning oil passing therethrough the foreign material removed from the crank case of the engine. Since the substances filtered out of the liquid by the filter 35 are derived from grease and heavy oils, said filter will hereinafter, for the sake of convenience, be referred to as "grease filter 35", and since the substances removed by the filter 36 are derived from motor oils, the filter 36 will be hereinafter referred to as "oil filter 36".

A crank case is designated diagrammatically at 37 and is normally provided with a filling opening 38 and an outlet or drain 39, the latter being normally closed by means of a plug (not shown). A flexible hose 40 is adapted to have detachable engagement at one end with the discharge 41 of the oil filter 36 while the other end is adapted to have removable engagement with the filling opening 38. A conventional valve or stop-cock 40' may be interposed in the conduit 40, preferably adjacent the discharge end thereof by which the flow of liquid into the crank case may be controlled. The end 40" may be removably connected to the stop-cock 40', the arrangement being such that a spray nozzle or high velocity nozzle (not shown) may be substituted therefor.

A transmission case is illustrated diagrammatically at 42 and is normally provided with a filling opening 43 normally closed by means of a plug 44 and an outlet drain 45 normally closed by means of a plug 46. A flexible hose 47 may have one end detachably connected to the discharge 48 of the grease filter 35 while the other end is adapted to be detachably connected to the filter opening 43.

In carrying out the process comprising my invention as specifically applied, for example, to the cleaning of a crank case, the drip pan 29 is placed under the drain opening 39 and the plug (not shown) removed from the said opening permitting the used oil to drain therefrom into the drip pan. The pump is then set into operation, draining the used oil from the pan 29 through the hose 28 and inlet 18, discharging it through the outlet 19, the distributing valve 30 at this stage being so manipulated as to cause the oil to be directed into the pipe 33 and thence into the drum 1 wherein it is stored.

After the used lubricating oil has been

drained from the crank case 37 and stored in the drum 1, valve 30 is manipulated to connect the pump discharge 19 with the pipe 34 leading to the oil filter 36, and the stop-

cock 40' closed. A suitable cleaning liquid, depending in quantity upon the capacity of the crank case to be cleaned, may be poured into the drip pan 29, and the hose 40 connected to the filler opening 38. This type of gear pump needs no priming, and hence a head of liquid is quickly built up at the stop-cock 40'.

When the pump 16 is in operation and the stop-cock 40' is closed, the liquid drawn through the inlet 18 is forced out at the outlet 19 and through the oil filter 36 and into the conduit or hose 40. Considerable pressure is then built up upon the pressure side of the pump which, if not dissipated, would "stall" the motor 9. To eliminate this difficulty I provide a port 49 communicating with the pressure side of pump 16. Said port may be normally closed by a valve 50 held in seated position by a spring 51. The valve when open permits communication between the pressure side of the pump and a compartment 52, which in turn is connected to the suction side of the pump by means of a port 53. The compartment 52 may be provided with a removable closure plug 54, slidably disposed in which is a stem 55 of valve 50. One end of the spring 51 is in contact with the valve 50, whereas the other end abuts the plug 54. The plug 54 may be movable inwardly and outwardly along the longitudinal axis of the stem 55, thereby providing a ready means for adjusting the compression of the spring 51. To maintain a constant compression of the spring 51, a key 56 may be provided in registering slots formed in the housing of the pump 16 and the plug 54 at the point of their threaded engagement. A cap 57 may be threadedly mounted upon the end of the housing of the pump 16.

When a predetermined pressure is reached on the pressure side of the pump 16, as determined by the compression of the spring 51, the valve 50 opens, establishing communication between the pressure and suction sides of the pump through compartment 52. Hence, while the stop-cock 40' is closed the pump will continue to operate up to a certain controllable maximum pressure whereupon the valve 50 opens and the churning or local circulating action occurs, thus relieving the motor 9 from undesirable overload.

Upon opening the stop-cock 40' the abnormal pressure in the hose 40 is immediately diminished, permitting the valve 50 to close under the action of the spring 51 and normal pumping action to be resumed. Hence, liquid under pressure is always available at the nozzle 40", and in addition an operator, after once starting the pump mo-

tor 9, may confine his attention to the crank case, and yet maintain perfect control of the pump, the motor being permitted to run continuously.

To clean or flush transmissions, differentials and the like, I place the drip-pan 29 under the drain 45, and remove the plugs 44 and 46. The hose 47 is then engaged with the filling opening 43 in a manner similar to the engagement of the hose 40 with the crank case 37. In the event that the oil or grease within the transmission 42 is too thick or viscous to readily flow out of the drain 45, a quantity of light distillate, such as gasoline, kerosene or the like, may be put in the drain pan 29 and the pump 16 actuated to cause the distillate to be circulated through the grease filter 35 and conduit 47 into the transmission case 42 and back into the drip-pan 29, thus the heavy oil or grease will be diluted or cut, whereby it will readily flow through the opening 45.

When the bulk supply of grease in the transmission case has been removed, the valve 30 is adjusted to connect the pump outlet 19 with the pipe 33 whereby the pump 16 will cause the mixture of grease and distillate to flow through the pipe 33 into the drum 1 wherein it is stored. When all of the above mixture has been stored in drum 1, the valve 30 is manipulated to cause the pump discharge 19 to be connected to the grease filter 35.

A fresh supply of cleaning oil, such as gasoline or the like, is put into the drip-pan 29 and the pump 30 caused to circulate the same through the grease filter 35 and hose 47, being discharged into the transmission case 42. The cleaning oil discharges from the transmission case 42 through the drain 45 into the drip pan 29 from which it is drawn by the pump 16 and again recycled through the filter 35 and transmission 42.

It is to be understood that I do not wish to be limited to the specific structure shown and described in carrying out my process, since the invention in its broadest aspects contemplates the use of any apparatus which will permit the control of the flow of cleaning fluid at the point where the cleaning is to take place.

I claim as my invention:

1. A process which comprises withdrawing used lubricant from a lubricant container, then introducing a limited quantity of cleaning fluid to the lubricant container, imparting to said cleaning fluid a cyclic circulation from said lubricant container to a point exterior thereof and back to said lubricant container, imparting to said cleaning fluid a suction flow for a limited distance immediately subsequent to removal from the lubricant container, then converting said suction flow to a positive pressure flow, filtering said cleaning fluid during its passage through the

cycle, positively controlling the flow of cleaning fluid immediately adjacent its discharge back into said lubricant container, and dissipating any back pressure created because of adjustment of the flow at the point of discharge into said lubricant container by returning excess from the pressure portion to the suction portion of said cycle.

2. A process which comprises withdrawing used lubricant from a lubricant container and isolating same, then introducing a limited quantity of cleaning fluid to the lubricant container, imparting to said cleaning fluid a cyclic circulation from said lubricant container to a point exterior thereof and back to said lubricant container, imparting to said cleaning fluid a suction flow for a limited distance immediately subsequent to removal from the lubricant container, then converting said suction flow to a positive pressure flow, filtering said cleaning fluid during its passagage through the positive pressure portion of the cycle, positively controlling the flow of cleaning fluid immediately adjacent its discharge back into said lubricant container, and dissipating any back pressure created because of adjustment of the flow at the point of discharge into said lubricant container by returning excess from the pressure portion to the suction portion of said cycle.

3. A process which comprises withdrawing used lubricant from a lubricant container, thereafter introducing a limited quantity of cleaning fluid to the lubricant container, imparting to said cleaning fluid a cyclic circulation from said lubricant container to a point exterior thereof and back to said lubricant container, filtering said cleaning fluid during said cyclic circulation while passing through the portion of the cycle exterior of said container, maintaining a flow of fluid during said cyclic circulation at a predetermined pressure, positively controlling the flow of fluid immediately adjacent its discharge back into said lubricant container, and dissipating any back pressure created because of adjustment of the flow at the point of discharge into said lubricant container by returning excess cleaning fluid from the pressure portion to the suction portion of said cycle.

4. A process which comprises withdrawing used lubricant from the lubricant container and isolating said used lubricant, introducing to the lubricant container a limited quantity of cleaning fluid, removing, by gravity, said cleaning fluid from the lubricant container, collecting said removed cleaning fluid in a pool, withdrawing cleaning fluid from said pool by suction and imparting a suction flow thereto for a limited distance, then converting said suction flow to a positive pressure flow, filtering said cleaning fluid during said positive pressure flow

to remove impurities therefrom, returning the filtered cleaning fluid to said lubricant container, and positively controlling the amount and pressure of flow to said lubricant container immediately adjacent the point of discharge of said cleaning fluid into said lubricant container, and dissipating any back pressure created because of adjustment of the flow at the point of discharge to said lubricant container by returning excess fluid from the pressure portion to the suction portion of the cycle.

5. A process which comprises withdrawing used lubricant from the lubricant container and isolating said used lubricant, introducing to the lubricant container a limited quantity of cleaning fluid, removing, by gravity, said cleaning fluid from the lubricant container, collecting said removed cleaning fluid in a pool, withdrawing cleaning fluid from said pool by suction and imparting a suction flow thereto for a limited distance, then converting said suction flow to a positive pressure flow, filtering said cleaning fluid during said positive pressure flow to remove impurities therefrom, returning the filtered cleaning fluid to said lubricant container, and positively controlling the amount and pressure of flow to said lubricant container by increasing or decreasing said flow immediately adjacent the point of discharge of said fluid thereinto relative to conditions in said lubricant container, and dissipating any back pressure created because of adjustment of the flow by returning excess from the pressure portion to the suction portion of the cycle.

6. A process which comprises withdrawing used lubricant from a lubricant container and isolating the used lubricant, then introducing to the lubricant container a limited quantity of cleaning fluid, imparting to said limited quantity of cleaning fluid a cyclic circulation from said lubricant container to a zone exterior thereof and back to said lubricant container, filtering said cleaning fluid during said cyclic circulation while passing through the portion of the cycle exterior of said container. Periodically interrupting the introduction of said cleaning fluid and causing the cleaning fluid in the lubricant container to partially drain from said container and, as the final portion of said cleaning fluid is leaving the container, resuming the introduction of the cyclically traveling cleaning fluid under pressure into the lubricant container.

7. A process which comprises withdrawing used lubricant from a lubricant container of an automotive vehicle and isolating same, periodically introducing to the lubricant container a limited quantity of cleaning fluid, periodically interrupting the introduction of said cleaning fluid, continuously removing by gravity a major portion of the

cleaning fluid from the lubricant container, collecting said removed cleaning fluid in a pool, continuously withdrawing cleaning fluid from said pool by suction and imparting a suction flow thereto for a limited distance, then converting said flow to a positive pressure flow, filtering said fluid during the positive pressure flow to remove impurities, and as the final portion of the cleaning fluid in the lubricant container is leaving the lubricant container, quickly resuming the introduction of a portion of said cleaning fluid, flowing under positive pressure, to the lubricant container.
